(57) **CLAIM**

The ornamental design for a pull reel, as shown and described.

DESCRIPTION

FIG. 1 is front elevation view of a pull reel showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is bottom plan view thereof;

FIG. 7 is a rear elevation view thereof showing the cable in an extended condition;

FIG. 8 is a referential front elevation view thereof showing a using condition; and,

FIG. 9 is a referential front elevation view thereof showing another using condition.

The cable in FIG. 7 is shown broken away for ease of illustration and to indicate indeterminate length.
